UNITED STATES PATENT OFFICE.

WILLIAM MATHEW LENG, OF HAVELOCK, ONTARIO, CANADA.

VALVE-GEAR.

1,253,503.

Specification of Letters Patent. Patented Jan. 15, 1918.

Application filed March 17, 1915. Serial No. 15,123.

To all whom it may concern:

Be it known that I, WILLIAM MATHEW LENG, a subject of the King of Great Britain, and resident of the town of Have-
lock, county of Peterborough, Province of Ontario, in the Dominion of Canada, have invented certain new and useful Improve-
ments in Valve-Gears, of which the follow-
ing is a specification.

10 The invention relates to improvements in valve gears as described in the present speci-
fication and shown in the accompanying
drawings that form part of the same.

15 The invention consists essentially in the
novel construction and arrangement of parts
whereby a plurality of levers are so assem-
bled as to vary the lead according to the
load.

20 The objects of the invention are particu-
larly to devise an efficient valve gear for
locomotives so that the said locomotives may
be operated successfully under the carrying
conditions in which they are used and gen-
erally to provide a valve gear free from com-
plications and of a durable nature.

25 In the drawings, Figure 1 is a diagram-
matic view showing the relation of the levers
and rods of the gear to the valve, the latter
being shown in longitudinal relation with
the steam chest and cylinder.

30 Fig. 2 is a diagrammatic view of the rods
and levers as they appear after having op-
erated the valve to give the proper lead for
starting the engine in a rearward direction.

35 Fig. 3 is a diagrammatic view of the rods
and levers as they appear after having op-
erated the valve to give the proper lead for
starting the engine in a forward direction.

40 Like numerals of reference indicate cor-
responding parts in each figure.

Referring to the drawings, 1 is the cylin-
der having the piston 2 operating therein
and the inlet and exhaust ports 3 and 4 ter-
minating at the valve seat 5.

45 6 is the steam chest mounted at the top
of the cylinder, and furnishing part of the
seat 5.

50 7 is a valve sliding on the valve seat 5
within the steam chest 6, said valve being

adapted on operation to close the front or 50
rear inlet port 3 to admit of steam entering
the cylinder through the other inlet to pro-
vide a lead accordingly as it is desired to
move the locomotive in a forward or rear-
ward direction.

55 The valve 7 is provided with a stem 8
projecting outwardly through the rear end
of the chest 6 and having flexibly connected
thereto at its outer end a rod 9 which ex-
tends rearwardly a short distance and is in 60
turn supported adjacent to its rear end by a
link 10 extending upwardly therefrom and
secured to one end of a bell crank 11, said
bell crank 11 being pivotally secured at its
center to a suitable bracket from the frame 65
of the locomotive and being pivotally con-
nected at its upper end to an operating rod
12 from the cab of the locomotive.

70 It will at once be apparent that in opera-
tion the rod 12 accordingly as it is moved in
a rearward or forward direction will raise
or lower the rod 9, the purpose for which
will be explained hereinafter.

75 13 is a lever provided at its upper end
with a slot 14 adapted to be engaged by a
headed pin 15 projecting at right angles
from the rear end of the rod 9, said lever
being pivotally connected at its lower end
to a crank rod 16 which extends rearwardly
and is pivoted to a crank lever 17 which in 80
turn is fixed upon a shaft 18 of one of the
driving wheels of the locomotive.

85 The lever 13 is secured at a point slightly
above its longitudinal center by a pivot 21
to a sleeve 19 slidably arranged on a hori-
zontal bracket 20 which is rigidly secured
at each end to the frame of the locomotive
and spaced therefrom.

90 22 is a radius rod at one end secured on
the pivot 21 and at the other end pivotally
secured to the upper end of the rod 23, the
latter being pivotally secured to the crank
rod 16 intermediate of the length of said
crank rod, said rods 22 and 23 and the inter-
mediate portions of the crank rod 16 and the 95
lever 13 forming four equal sides all piv-
otally joined.

Adjacent to the point of connection be-

tween the rods 22 and 23 a substantially rectangular frame 24 is rigidly mounted centrally on a shaft 25 which in turn is suitably journaled in bearings from the locomotive frame.

The frame 24 and shaft 25 are adapted to be rotated by means of a rod 26 secured slightly above and to one side of the center of said frame and extending to the cab of the locomotive.

It will be apparent that horizontal motion imparted to the rods 22 or 23 will be transmitted to the lever 13, moving the upper end thereof in a backward or forward motion as the case may be and consequently moving the valve 7 on its seat and in order to bring this movement under the control of the operating rod 26 toggles 27, 28 and 29 forming a substantially N-shaped lever operating on two fixed points 30 and 31 at opposite sides of the frame 24 toward the upper and lower ends of said frame, are provided, the toggle members 27 and 28 being pivotally secured at the points 30 and 31 and the central toggle member 29 connecting the other ends of said toggles 27 and 28 and itself centrally and pivotally secured to the pivot joint 32 of said rods 22 and 23.

The starting of the locomotive may be greatly facilitated by allowing a considerable quantity of steam to enter the cylinder prior to starting and as will have been seen by the foregoing description in combination with the drawings a convenient means of varying the amount of this lead and of reversing the lead from one inlet to another accordingly as the locomotive is to be moved in a forward or rearward direction, is provided without interfering with the ordinary valve operating mechanism.

It will be apparent that the amount of lead given in either direction depends upon the distance between the point where the pin 15 on the end of the rod is located within the slot 14 and the point 21 where the lever 13 is pivoted to the sleeve 19 and to the radius rod 22 and this distance may be varied according to the load to be carried by means of the operating rod 12, as for instance when said rod is pulled the bell crank 11 raises the rod 9 and the pin 15 slides toward the upper end of the slot 14 and this increases the leverage of said rod 13, while movement of said rod 12 in the opposite direction will of course have the effect of decreasing the leverage of said rod 13.

When it is desired to move the locomotive in a rearward direction and a lead is required the rod 26 is drawn backwardly pulling the upper end of the frame 24 in the same direction and causing the loosely journaled ends of the N-shaped member to tilt upwardly and draw the radius rod 22 rear-

wardly and as the lever 13 is secured thereto and is adapted to move in a horizontal direction by means of the sleeve 19 the said lever will carry with it the rod 9 and thus draw the valve 7 rearwardly to admit of steam entering the foremost inlet port.

To supply the lead from the rear steam inlet port to move the locomotive in a forward direction the operating rod 26 is pushed forwardly causing the radius rod 22 to move in the same direction and to carry the lever 13 and sleeve 19 forwardly, which in turn pushes the rod 9 and moves the valve 7 to the forward end of the steam chest leaving an opening through the rearmost inlet port 3.

What I claim is:

1. A valve gear comprising a plurality of levers pivotally joined together, a valve rod adjustably secured to one of said levers, a crank rod pivotally secured to said adjusting lever, a reversing mechanism pivotally secured to said crank rod by one of said levers and having a pivot point movable in oblique directions in relation to a horizontal line drawn through its center and a crank secured to said crank rod.

2. A valve gear comprising a reversing mechanism formed of a tilting frame and pivoted levers arranged on said frame, a plurality of rods pivotally joined to said levers, an adjusting lever pivotally joined to one of said rods, a cranked rod joined to the other of said rods and to the end of said adjusting lever, a crank joined to said crank rod and a valve rod adjustable in said adjusting lever.

3. A valve gear comprising a reversing gear formed of a tilting frame, a plurality of toggles operating from two fixed pivoted points, a crank rod, a crank, a valve rod, a lever adjustably connecting said crank rod to said valve rod, a rod pivotally connecting said crank rod to said toggles and a rod pivotally connecting said adjusting lever to said toggles.

4. A valve gear comprising a reversing gear formed of a tilting frame carrying an N-shaped lever composed of three toggles operating from two fixed pivoted points, a crank rod, a crank, a valve, a rod pivotally connecting the central toggle with said crank rod, an adjusting lever having a longitudinal slot at its upper end in which said valve rod is adjusted and at its lower end pivotally connected to said crank rod, a rod pivotally connecting said central toggle with said adjusting lever and a sliding guide connected with the pivotal point of said adjusting lever and connecting rod.

5. A valve gear comprising a valve rod, a bell crank lever linked to said valve rod adjacent to the end thereof, a reach rod ex-

tending from said bell crank, a slotted lever adjustably secured to the end of said valve rod adjacent to said link connections, a reversing mechanism having a pivotal point 5 movable in oblique directions in relation to the horizontal, a crank rod at the end thereof directly connected to said slotted lever, a plurality of rods pivotally connecting said slotted lever and said crank rod through

said movable pivotal point and a crank operating said crank rod.

Signed at the village of Havelock, Ontario, this 10th day of December, 1914.

WILLIAM MATHEW LENG.
